UNITED STATES PATENT OFFICE.

EDWARD KNAUSS, OF MOUNT VERNON, NEW YORK, ASSIGNOR TO K. P. PRODUCTS COMPANY, INC., OF NEW YORK, N. Y., A CORPORATION OF NEW YORK.

GOVERNOR FOR INTERNAL-COMBUSTION MOTORS.

Application filed November 2, 1920. Serial No. 421,358.

To all whom it may concern:

Be it known that I, EDWARD KNAUSS, a citizen of the United States, residing at Mount Vernon, county of Westchester, and 5 State of New York, have invented new and useful Improvements in Governors for Internal-Combustion Motors, of which the following is a specification.

My invention relates to governors for internal combustion motors and has for its object to provide a governor for this purpose which will be more efficient and accurate in its action, more easily and accurately regulated, more durable and less costly to construct than those heretofore in use.

With these and other objects in view, which will be more particularly set forth in the specification, my invention consists in the novel details of construction and combinations of parts hereinafter disclosed and particularly pointed out in the claims.

Referring to the accompanying drawings:

Figure 1 is a sectional view on the line A—B of Figure 3.

Figure 2 is an elevation partly in section and partly broken away.

Figure 3 is a section on the line E—F of Figure 1.

Figure 4 is a plan view looking upward.

Figure 5 is an enlarged detail partly in section of the piston, cylinder and needle valve.

Like numerals designate like parts in all the views.

My governor is provided with a casing or body 1, which is formed of the shells 2 and 3, which are secured together by forcing the lower end of the shell 2 over the contracted portion 4 of the shell 3 until it rests on the shoulder 5. The shell 2 is provided with a flange 2^a which is adapted to be secured to the manifold of an internal combustion engine and the shell 3 with a flange 3^a adapted to be secured to the flange of a carburetor by bolts, not shown, which pass through the flange on the manifold both flanges on my governor and the flange on the carburetor. The upper portion of the shell 3 is reduced in diameter and machined to form a neck 6. Formed integral with the neck 6 is a spider 7 which supports a cylinder 8 upon which is mounted a disc 9.

The cylinder 8 is provided with a port 10 which discharges above the disc 9 and may 55 be regulated by a needle valve 11. A cap 12

is adapted to cover the chamber 13 in which the needle valve is mounted, and may be secured in position by a seal 14, so that the regulation of the needle valve 11, with reference to port 10, can not be disturbed without breaking the seal 14. Secured in the base of the casing 3 is a spider 15 provided with an upstanding cylinder 16 which may or may not be provided with an air vent 17. The spider 15 secures the bushing 15^a in the 60 casing 3. Mounted on a guide stem 18, which extends into the cylinder 16, is a head 19, having a tubular piston 20, the upper end of which is formed to fit closely and accurately in the cylinder 8 and is adapted to 65 reciprocate therein and act as a dash pot. It is apparent that the stem 18 and the cylinder 16 will also act as a dash pot if the vent 17 is omitted or is not too large to prevent this action.

The piston 20 is provided with a reduced section 21, which when the parts are at rest, as shown in Figure 1, begins below the port 10 and extends below the lower end of the cylinder 8. Below the section 21 is the lower 70 piston section 22, which is slightly tapered as shown in Figure 5.

The lower piston, section 22, fits somewhat loosely in the cylinder 8 but the area of the clearance between the lower piston section 80 22 and the wall of the cylinder 8 is less than the area of the port 10.

Externally mounted on the neck 6 is a concentric valve 23. In the upper end of the valve 23 are cut two notches 24, which not 90 only serve to gradually close the port between the chambers 26 and 27 when the valve 23 has been lifted until its highest point is level with the disc 9 but leave uncovered triangular ports of small area when 95 the piston 20 is in contact with the head of the cylinder 8. These triangular ports, which then remain uncovered by the disc 9, are of such area that they will supply sufficient mixture to prevent the engine from 100 missing or reduce the charges of mixture beyond the point where they will not ignite and yet will not supply sufficient mixture to cause further acceleration of the engine speed.

The operation of my invention is as follows: When the engine is running slowly the travel of mixture from the carburetor through my governor to the engine will be comparatively slow and the impact of the 110

2

mixture on the head 19 will not be sufficient to lift the head and the parts to which it is secured. Under these conditions, there will be no substantial difference in pressure in the chambers 26 and 27. The weight of the head 19 and the parts to which it is secured are such however that when the flow of the mixture, and its velocity is sufficiently increased by any increase in the engine speed, 5 the head 19 will be lifted carrying with it the piston 20 and the valve 23. The valve 23, as it is raised, restricts the port leading from the chamber 26 to the chamber 27 and thereby causes the pressure in the chamber 27 to 10 fall below the pressure in the chamber 26. If the flow of mixture is sufficiently rapid, the head 19 will be elevated until the reduced portion 21 of the piston is opposite the port 10 and the upper end of the lower 15 piston section 22 is within the cylinder. The negative head in the chamber 27 will then be communicated to the cylinder 8 where it will be reduced by the leakage past the lower section 22 of the piston, but will tend to further 20 elevate the piston and valve 23. As the valve 23 is raised and the port between the chambers 26 and 27 is closed, this difference in pressure in the chambers 26 and 27 is rapidly increased, if the engine speed is 25 maintained until it is sufficient to raise the piston 20 until its head contacts with the head of the cylinder 8 thereby reducing the port between the chambers 26 and 27 to the unclosed portions of the angular ports in the 30 upper end of the valve 23. The angular ports easily and gradually cut down the flow of mixture to such an amount as will prevent further acceleration of the engine speed, while at the same time supplying sufficient 35 quantities of mixture to keep the engine running smoothly and prevent missing. It will also be apparent that as the tapered section 22 of the piston 20 passes into the cylinder the leakage between the piston and the cylinder 40 walls is decreased and the net head acting to force it upward is increased accordingly.

By regulating the needle valve 11 so as to partially close, more or less, the port 10, the ratio of the clearance area about the lower 45 piston section 22 to the effective area of the port 10 may be varied at will, causing a corresponding variation in the engine speed necessary to lift the piston and close the valve 23. As the moving parts move with a minimum of friction, my governor quickly 50 and accurately responds to the varying conditions of the flow of mixture through it and to the varying pressures in the chambers 26 and 27 caused by the closing of the valve 23, 55 and the action of these variations of pressure may be regulated by the needle valve 11, thereby easily enabling the operator to accurately regulate the speed of the engine to which it is attached within wide ranges. 60 65 The primary means which initiates the clos-

ing movement of the valve 23 is the head 19, and the engine speed at which the closing movement of the valve 23 is initiated may be regulated by substituting heads 19 of varying size or weight or bushings 15^a of varying 70 interior diameters. The secondary means which is adapted to complete but cannot initiate the closing movement of the valve 23 is the piston 22, the action of which is regulated by the needle valve 11. 75

Claims.

1. A governor for internal combustion motors comprising in combination a port through which explosive mixture may pass from the source of supply to the engine, a valve adapted to reduce the area of said port, primary automatic means adapted to partially close said valve and secondary automatic means actuated by the difference in pressure on opposite side of said valve 80 adapted to continue but not to initiate the closing movement of said valve.

2. A governor for internal combustion motors comprising in combination a port through which explosive mixture may pass 90 from the source of supply to the engine, a valve adapted to reduce the area of said port, primary automatic means adapted to partially close said valve, secondary automatic means actuated by the difference in 95 pressure on opposite sides of said valve adapted to continue but not to initiate the closing movement of said valve and manual means for regulating the action of said difference in pressure on said secondary means. 100

3. A governor for internal combustion engines comprising in combination a port through which explosive mixture may pass from the carburetor to the engine, a valve adapted to reduce the area of said port, primary means, actuated by the impact thereon of the explosive mixture adapted to partially close said valve and secondary means actuated by the difference in pressure on opposite sides of said valve adapted to continue but not to initiate the closing movement of said valve. 105

4. A governor for internal combustion engines comprising in combination a port through which explosive mixture may pass 115 from the carburetor to the engine, a valve adapted to reduce the area of said port, primary means, actuated by the impact thereon of the explosive mixture adapted to partially close said valve, secondary means actuated by the difference in pressure on opposite sides of said valve adapted to continue but not to initiate the closing movement of said valve and manual means for regulating the activity of said secondary means. 120

5. A governor for internal combustion motors comprising in combination a port through which explosive mixture passes from the carburetor to the engine, a valve adapted to reduce the area of said port, pri- 125

mary means actuated by impact of the explosive mixture adapted to partially close said valve and secondary means actuated by the difference in pressure on opposite sides of said valve adapted to continue the closing movement of said valve.

6. A governor for internal combustion motors comprising in combination a port through which explosive mixture passes from the carbureter to the engine, a valve adapted to reduce the area of said port, primary means actuated by impact of the explosive mixture adapted to partially close said valve, secondary means actuated by the difference in pressure on opposite sides of said valve, adapted to continue the closing movement of said valve and manual means for regulating the action of said difference in pressure on said secondary means.

7. A governor for internal combustion motors comprising in combination, a port through which explosive mixture may pass from the carbureter to the engine, a valve adapted to partially, but not wholly, close said port, a head attached to said valve and mounted in the path of the mixture passing through said governor and adapted to be actuated by the impact of the mixture and

partially close said valve, a cylinder, a piston mounted in said cylinder and connected to said valve and said head, chambers on either side of said valve and a port in the wall of said cylinder in communication with said cylinder and the chamber between the valve and the engine.

8. A governor for internal combustion motors comprising in combination, a port through which explosive mixture may pass from the carbureter to the engine, a valve adapted to partially, but not wholly, close said port, a head attached to said valve and mounted in the path of the mixture passing through said governor and adapted to be actuated by the impact of the mixture and partially close said valve, a cylinder, a piston mounted in said cylinder and connected to said valve and said head, chambers on either side of said valve, a port in the wall of said cylinder in communication with said cylinder and the chamber between the valve and the engine, and manual means for partially closing the port in the cylinder wall.

Signed at New York, this 25th day of October, 1920.

EDWARD KNAUSS.
